UNITED STATES PATENT OFFICE

2,492,066

BALANCE DEMONSTRATING DEVICE

Henry C. Schildmeier, Indianapolis, Ind.

Application October 23, 1947, Serial No. 781,670

7 Claims. (Cl. 35—10)

1

This invention relates to a device for demonstrating static and dynamic balance and unbalance in rotating bodies.

The chief object of the present invention is to provide a support for a circular rotatable mass and selectively associate therewith a plurality of small mass members for visually indicating states and kinds of unbalance and combinations thereof and the principles of correction for same.

The chief feature of the present invention resides in providing a support with coaxially rotatable circular mass of appreciable amount, and substantially symmetrical, and with a plurality of sockets on opposite sides thereof, at least two of which on the same side are diametrically disposed, certain of the opposed sockets being longitudinally aligned.

Another feature of the invention resides in having the aligned sockets comprising continuations of each other.

A further feature of the invention resides in having the sockets threaded to take threaded stems of the small mass members, and selectively and interchangeably.

Other objects and features of the invention will be set forth more fully hereinafter.

The full nature of the invention will be understood from the accompanying drawings and the following description and claims.

In the drawings:

Fig. 1 is a perspective view of one embodiment of the invention showing two of the small mass members in diagonally disposed relation.

Fig. 2 is a central sectional view through the same.

Fig. 3 is an elevational view of the device with two of the members diametrically disposed.

Fig. 4 is a similar view with two of the members disposed oppositely and in longitudinally aligned relation.

In the drawings 10 indicates a spindle or the like which can be grasped and held in one hand, see dotted lines Fig. 1. It is stepped as at 11 and the end is slotted as at 12. Mounted thereon is the bearing 13 centrally disposed in the symmetrical circular, relatively large mass 14. The slot provides for spindle-bearing retention against axial separation. Bearing 13 may be of anti-friction character so that mass 14 is readily rotatable about the spindle axis.

Herein the periphery 15 of said mass includes considerable concentration so that when the mass is rotated the effect of centrifugal force, etc., is emphasized.

Disposed in diametral relation and in imme-

5

diate proximity to periphery 15 are the threaded holes 16, the axes of which are parallel to each other and the axis of rotation. Thus two such holes provide four sockets and these are identical.

Obviously the aforesaid structure is of substantially balanced type.

At least two substantially similar small mass members are provided and same are interchangeably receivable by the said sockets. Each member comprises a threaded stem 17, an intermediate polygonal portion 18 and ornamental end 19. Shoulder 20 constitutes a stop limiting the seating of the stem in the socket.

15 When no members are applied to the circular body it can be revolved upon the spindle axis and the body is substantially in dynamic and static balance.

When one member is applied to the body the result is there is present both dynamic and static unbalance and the body has both a wobble and hopping combined action.

When a second member is applied directly opposite the first member, see Fig. 4, the result is 20 that the body is dynamically but not statically balanced so that rotation includes a hopping action.

When a second member is applied diagonally opposite, see Figs. 1 and 2, the structure is statically balanced but dynamically unbalanced and the rotation includes a wobble action.

When a second member is applied diametrically opposite and on the same side, see Fig. 3, the body is both dynamically and statically balanced 25 and the rotation is true, that is, without wobble or hopping action.

A device of this type with a spindle one quarter by four or so inches and a body of approximately three inches in diameter by a half inch or so at its thickest part very effectively and visually demonstrates unbalance and proper balancing such as found in bent or damaged vehicle wheels and rims and by virtue of unbalanced tires, etc., thereon.

30 45 While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. A device for visually demonstrating dynamic

and static unbalance and correction comprising a spindle adapted for hand gripping of the same, a circular appreciable mass structure having a diameter at least three times the maximum thickness of the mass, the mass having its greatest concentration at the periphery rotatably mounted on said spindle, said structure on opposite sides having a plurality of arcuately spaced sockets in close proximity to the periphery thereof and where the concentration is greatest, and at least a pair of smaller mass members for selective reception by the sockets.

2. A device as defined by claim 1 wherein the sockets on opposite sides are aligned with each other.

3. A device as defined by claim 2 wherein the aligned sockets comprise continuations of each other.

4. A device as defined by claim 3 wherein the sockets are of threaded type and identical and the smaller mass members are substantially identical and interchangeably receivable by the sockets.

5. A device for visually demonstrating dynamic and static unbalance and correction comprising a spindle adapted for hand gripping of the same, a circular appreciable mass structure having a diameter at least three times the maximum thickness of the mass, the mass having its greatest concentration at the periphery, rotatably mounted on said spindle, having a plurality of arcuately spaced sockets in close proximity to the periphery thereof and where the concentration is greatest, and at least a pair of smaller mass members for

selective reception by the sockets, each socket being of threaded type and each smaller mass member including a threaded, socket receivable stem.

6. A device for visually demonstrating dynamic and static unbalance and correction comprising a spindle adapted for hand gripping of the same, a circular appreciable mass structure having a diameter at least three times the maximum thickness of the mass, the mass having its greatest concentration at the periphery, rotatably mounted on said spindle, having a plurality of arcuately spaced sockets in close proximity to the periphery thereof and where the concentration is greatest, and at least a pair of smaller mass members for selective reception by the sockets, at least two of the sockets on each side being disposed in diametral relation.

7. A device as defined by claim 6 wherein the sockets on opposite sides are aligned with and comprise continuations of each other.

HENRY C. SCHILDMEIER.
